PAUL MÜCKE, OF SCHÖNAU, GERMANY.

FLOWER-VASE.

1,045,589.

Specification of Letters Patent. Patented Nov. 26, 1912.

Application filed March 13, 1911. Serial No. 614,229.

To all whom it may concern:

Be it known that I, PAUL MÜCKE, a subject of the King of Prussia, residing at Schönau, in the Kingdom of Prussia, Germany, have invented certain new and useful 5 Improvements in Flower-Vases, of which the following is a specification.

This invention relates to a flower-vase composed of a certain number of tubes of 10 small diameter mounted upon a common base. According to the invention the tubes are bent in zig-zag shape so that the stem of the flower can be clamped in at any height which permits a very graceful arrangement 15 of the flowers.

In the accompanying drawings the improved flower-vase is shown:—

Figure 1 is an elevation of the improved flower-vase. Fig. 2 shows one tube with a 20 flower.

The tubes of which the vase is composed are bent in zig-zag so that the concavities

of the one side are nearly in vertical alignment with the concavities of the other side.

The stem of the flower which is placed in 25 such a tube is thus clamped in between the consecutive concavities without being broken, so that it will be possible to securely fix in said tubes at a suitable height even flowers with very short stems. 30

I claim:

An improved flower vase consisting of a base plate and of a certain number of tubes mounted upon said plate and corrugated from the bottom to the top so that the stalks 35 of the flowers are securely maintained at any convenient height by said corrugations.

In witness whereof I have hereunto set my hand in the presence of two witnesses.

PAUL MÜCKE.
